UNITED STATES PATENT OFFICE.

SAMUEL M. RHOADS AND ADAM H. HAMRICK, OF PHILADELPHIA, PENNSYLVANIA, ASSIGNORS TO PHILADELPHIA BREWERY APPLIANCE COMPANY, A CORPORATION OF NEW JERSEY.

RACKING DEVICE.

SPECIFICATION forming part of Letters Patent No. 716,346, dated December 16, 1902.

Application filed November 22, 1901. Serial No. 83,237. (No model.)

To all whom it may concern:

Be it known that we, SAMUEL M. RHOADS and ADAM H. HAMRICK, citizens of the United States, and residents of the city and county of Philadelphia, State of Pennsylvania, have invented certain new and useful Improvements in Racking Devices, of which the following is a specification.

Our invention relates to improvements in racking devices, and more particularly to improvements in that class of devices for filling barrels, kegs, or other packages in which are combined a stationary filling-head with a movable filling-tube, the object of our invention being to furnish a filling-tube and filling-head which after the barrel, keg, or package is completely filled with liquid may be operated to conjointly form a seal which will prevent all escape of fluid from the tube or head between the times that they are removed from one package and secured to another package.

In the accompanying drawings, forming part of this specification, and in which similar letters of reference indicate similar parts throughout the several views, Figure 1 is a central sectional elevation through a barrel and through a filling head and tube embodying our improvements, the filling-tube being lowered to the bottom side of the barrel; Fig. 2, a sectional elevation through the filling-head and filling-tube, showing their position when the latter is drawn up against the former to form a seal; and Fig. 3, a side elevation of the lower part of the filling-tube.

35 *a* is the filling-head and *b* the filling-tube of a racking device. The head and tube may be of any of the well-known general constructions, the former being adapted to be secured at its bottom to a bung in any well-known 40 manner and the latter being adapted to slide through the former, so that its lower end, through which the liquid is discharged, may reach the lower side or end of the barrel to be filled, its upper end being connected in 45 the usual manner with the tank or cask which holds the liquid to be placed in the barrel.

For the purposes of our invention the filling-tube *b* is closed at the bottom, as shown at *c*, and the sides of the tube above the bot-

tom are furnished with perforations *d*, through which when the tube is lowered the liquid can escape, said perforations or openings *d* being made preferably large, so as to prevent foaming of the liquid.

e is a piece, preferably of rubber and conical, as shown, carried by the lower end of tube *b*, which is adapted when the tube is fully lifted not only to form a stop to limit the upward movement of the tube, but to engage with the bottom of the head *a*, as shown in Fig. 2, 60 to form a plug or valve which completely and effectually closes the lower end of the head. We prefer to form the lower end of the head *a* with a countersink *f*, which is adapted to receive the washer *e*. For convenience in construction said countersink *f* is formed on an annular ring *g*, which is adapted to be screwed to the head *a*, as shown. The filling-head *a* is provided at a suitable point with a threaded passage *h* for the reception of an overflow-pipe. It will be noticed that the ring *g* forms a shoulder for the support of the packing *k*, which is interposed between said ring and a shoulder *l* on said head and placed around the lower end of the latter, whereby by properly rotating said ring said packing may be compressed, so as to form a tight joint with said bung when the head is fitted in the latter. The ring depends from the head into the barrel, and its 80 countersink *f* forms a seat which may be effectually closed by the valve *e* when the tube *b* is fully raised. A barrel, keg, or other package having been completely filled with liquid, the filling-tube *b* is drawn up until the valve 85 *e* completely closes the countersink in the lower end of the filling-head *a*. When this is done, the filling-head *a* may be removed from the package without the possibility of any leakage of fluid therefrom. The conical valve *e* is fitted on a neck depending from the lower end of the tube *b*, which may be removed and replaced.

Having thus described our invention, we claim as new and desire to secure by Letters 95 Patent—

1. In a racking device, a tubular head having its lower end adapted to be inserted into

- a bung, a packing encircling said end, an adjustable ring on said end forming on top a shoulder against which said packing rests and having a seat at bottom and a filling-
5 tube which is passed through said head and provided at its lower end with a valve, the latter being adapted to close against said seat.
2. In a racking device, of the character stated, the combination with a filling-tube
10 having a valve at its lower end and openings above the same, of a head, which encircles a portion of said tube outside of the vessel to be filled, and means for firmly connecting said head with the bung of said vessel, said
15 means consisting of packing on said head, a shoulder on said head above said packing, and a ring on said head below said packing, said ring forming a shoulder on which the under side of said packing is rested and hav-
20 ing a seat for said valve.

3. In a racking device, of the character stated, the combination with a filling-tube having a valve at its lower end and openings above the same, of a head, which encircles a portion of said tube outside of the vessel to 25 be filled, and means for firmly connecting said head with the bung of said vessel, said means consisting of packing on said head, a shoulder on said head above said packing, and a ring on said head below said packing, 30 said ring forming a shoulder on which the under side of said packing is rested and having a seat for said valve, said ring being adjustably connected with said head.
